UNITED STATES PATENT OFFICE

165,218

RESTAURANT BUILDING

Melvin E. Coleman, Waco, Tex., assignor to Chuc-Wagun System Incorporated, Waco, Tex., a corporation of Texas

Application October 2, 1950, Serial No. 12,423

Term of patent 7 years

(Cl. D13—1)

To all whom it may concern:

Be it known that I, Melvin E. Coleman, a citizen of the United States, residing at 1611 Herring Avenue, Waco, State of Texas, have invented a new, original, and ornamental Design for a Restaurant Building, of which the following is a specification, reference being had to the accompanying drawing, forming part thereof.

Figure 1 is a side elevation of a restaurant building showing my new design;

Figure 2 is a front view; and

Figure 3 is a rear view.

The appearance of the opposite side of the building is substantially similar to the side shown in Fig. 1, with the exception that the width of the window is less, the rear extremity being visible through the window in Fig. 1.

I claim:

The ornamental design for a restaurant building, as shown and described.

MELVIN E. COLEMAN.
